UNITED STATES PATENT OFFICE.

HERMANN EMIL SCHRADER, OF HAMBURG, GERMANY.

BOTTLE-FILLING MACHINE.

SPECIFICATION forming part of Letters Patent No. 358,575, dated March 1, 1887.

Application filed March 17, 1886. Serial No. 195,554. (No model.) Patented in Germany February 21, 1885, No. 33,137.

To all whom it may concern:

Be it known that I, HERMANN EMIL SCHRADER, engineer, of the city of Hamburg, in the German Empire, have invented a new and useful Improvement in Bottle-Filling Machines, of which the following is a specification, reference being had to the accompanying drawings.

This invention has for its object the drawing off of liquid from casks or other closed vessels into bottles without the exposure of the liquid to any other air than that contained in the bottles to be filled.

In the use of a bottle-filling machine with my improvement the quantity of air expelled from the bottles while filling passes through the filling-machine and over into the casks, the process of filling the bottles proceeds in a better and more uniform way than in filling-machines of hitherto known construction, and for drawing beer from casks into bottles my improvement is of especial value, as it causes less scumming of the liquid.

In the accompanying drawings, Figure 1 is a perspective view showing a bottling-machine constructed according to my invention, in connection with a cask from which the liquid is to be drawn off into bottles. Fig. 2 is a transverse vertical section of the machine, taken directly through one of the filling-tubes. Fig. 3 is a transverse vertical section of the air-tight liquid-receiver and attached parts, taken in the center of the machine between the bottling-tubes. Fig. 4 is a transverse section, on a larger scale than Figs. 2 and 3, of one of the bottling-tubes and its immediate appurtenances.

Similar letters of reference indicate corresponding parts in the several figures.

A designates a receiving-vessel, which is provided with a cover, A', by which it can be closed hermetically, and is supported on standards. This vessel is furnished with a flexible hose, h, and coupling-tube e, by which it can be put in connection with the tap k of a cask, R. The inner mouth of the coupling-tube e is capable of being closed by a valve, v, connected with a float, s. Prior to the commencement of the filling operation this float occupies a lower position than shown in the drawings, and valve v is then open.

By opening the tap k of the cask liquid from the latter is permitted to enter A, and a corresponding quantity of air from A is permitted to pass from the said vessel into the cask by a flexible hose, h', and coupling-tube k', connected with said vessel at the top thereof, until, by the rising level of the liquid in the vessel A, the float s closes valve e. This level must be of an adjusted height, as will be understood from the further description.

In the lower part of the front of the vessel A are a number of openings corresponding with the number of bottles which are to be filled at a time by the machine, and into each of these openings is screwed (as best shown in Fig. 4) a metal socket, C, which has a central bore to receive within it a metal cylinder, d*, which forms the head or upper part of the filling-tube d, and which is fitted to slide freely within the said bore. On the upper part of this cylinder or tube head d*, above the socket C, there is a flange, i, and below this flange there are lateral openings n. Below the socket C there is screwed on the said socket a nut, f, between which and the bottom of the said socket is a spiral spring, which exerts a tendency to push down the said cylinder as far as permitted by the flange i, and so cause the openings n to be tightly closed within the bore of the socket, as shown in Fig. 4, and so prevent any liquid from passing from the vessel A to the filling-tube d, the cylinder or filling-tube head d* thus constituting a valve to the said tube, and the socket C forming the seat of the said valve.

Below the nut f there is placed on the filling-tube an india-rubber ring or gasket, o, of a shape to fit and hermetically close the mouth of the bottle to be filled. The exit-opening d of the filling-tube is on one side near the end thereof, and in the lower end of the said tube is secured the open lower end of the smaller tube g, which constitutes the vent-tube, and which is long enough for its open upper end to be always above the surface of the liquid in the vessel A.

When for filling a bottle the neck of the latter is put over one of the filling-tubes with its mouth against the ring o and the bottle then pushed upward, the filling-tube rises and brings its valve-opening i above the socket n,

as shown in Fig. 2, and so permits the liquid to run from the vessel A through the tube into the bottle. The air expelled from the bottle by the entering liquid passes through the vent-tube *g* above the liquid level *m* into the vessel A, and thence through coupling-tube *h'* and hose *h* into cask R.

As the liquid is drawn off from vessel A the float *s* descends and valve *v* opens to allow new liquid to pass from cask R into vessel A; but as the liquid enters the vessel the float will rise and would close the valve in time to prevent any liquid from closing the upper ends of the vent-tube. The level of the liquid is thus maintained nearly constant in the vessel A.

The bottles may be lifted and held up to the rings *o* by hand, or by means of lever-like supports turning on bolts and springs *z'*, as will be understood with reference to the drawings.

It will be observed that the filling-tube *d* and its head *d'* form a passage continuous from the valve at the inner end of the head to the outer end of the tube, and said tube and head may move or slide as one piece. The spring *t*, which is applied around the exterior of the filling-tube *d*, acts therefore directly to close the valve, and the pressure within the vessel, which may be variable, is not depended on for that purpose. The vent-tube *g* is fixed relatively to and movable with the filling-tube *d*, and such vent-tube extends directly through and beyond the valve, being tightly fitted in the valve.

What I claim as my invention, and desire to secure by Letters Patent, is—

1. The combination, with an air-tight receiv-

ing-vessel provided with a liquid-inlet pipe and a float and valve for closing said pipe, and also provided with an air-outlet pipe and an opening for a bottle-filling tube, of a valve-seat 40 at the inner end of said opening, a filling-tube sliding in said opening, constructed at the outer end to receive a bottle, and having a valve at the inner end for closing on said seat, the said filling-tube affording a continuous passage from 45 the valve to its outer end, and having an internal vent-tube movable with it and prolonged through the valve and within the vessel, and a spring applied around the exterior of the filling-tube for depressing said tube to close the 50 valve, substantially as herein described.

2. The combination, with the air-tight vessel A, having an opening in its lower part, of a socket, C, inserted from the outside into said opening, and having a valve-seat formed upon 55 its inner end, the filling-tube *d*, having a cylindric head, *d'*, sliding in said socket, and forming a continuous passage from the inner end of the head to the outer end of the tube, a flange, *i*, on said head, and lateral openings 60 *n* below said flange, said flange and openings constituting a valve, the vent-tube *g*, fixed to and movable with the filling-tube, and prolonged through the valve and within the vessel, and a spring applied around the exterior 65 of the filling-tube and serving to depress or move it outward to close said valve, substantially as herein described.

HERMANN EMIL SCHRADER.
